CLAIM

The ornamental design for a table attachment for kettle barbecue, as shown and described.

DESCRIPTION

FIG. 1 is a left front perspective of a table attachment for kettle barbecue, showing my new design;

FIG. 2 is a side elevational view, the opposite side elevational view being a mirror image thereof the broken-line representation of the kettle barbecue being included solely for illustrative purposes, forming no part of the claimed design;

FIG. 3 is a top plan view thereof;

FIG. 4 is a bottom plan view thereof;

FIG. 5 is a rear elevational view thereof; and,

FIG. 6 is a front elevational view thereof.
